CONTAINER

Henry K. Powell, Chicago, Ill., assignor, by mesne assignments, to President and Directors of the Manhattan Company, a corporation of New York, trustee for Gibson Patent Containers, Ltd., a corporation of New South Wales, Australia

Application May 6, 1935, Serial No. 19,915

2 Claims. (Cl. 229—5.5)

The present invention relates to collapsible containers, and has particular reference to improvements in the construction of fibrous collapsible containers of the type which may be employed for packaging ice cream and the like.

A principal object of the invention is to provide a collapsible fibrous container which may be erected easily from flattened condition by the user.

10 An additional object is to provide a collapsible tubular container which may be employed for packaging ice cream and the like and which may be constructed entirely of paper board or similar material.

15 A further object is the provision of a container of the type described having a novel and effective bottom interlocking structure.

These and other objects will be observed upon a consideration of the following description of 20 the invention and by reference to the accompanying drawings, in which—

Fig. 1 is a fragmentary outside view of a container constructed in accordance with the invention;

25 Fig. 2 is a top view of a bottom member for interlocking with the container shown in Fig. 1;

Fig. 3 is a plan view of the blank from which the body portion of the container is constructed;

30 Fig. 4 is a fragmentary sectional view taken along line 4—4 of Fig. 1 and showing the interlocking tabs in position to be secured to the body portion of the container;

Fig. 5 is a fragmentary view similar to Fig. 4 and shows the interlocking mechanism in secured 35 relation;

Fig. 6 is a view similar to Fig. 5 and shows a modified method of interlocking the bottom member to the body portion of the container;

Fig. 7 is a plan view of a modified form of the 40 container in which the bottom member is integrally secured to the body portion;

Fig. 8 is a fragmentary sectional view taken along line 8—8 of Fig. 7;

Fig. 9 is a fragmentary vertical section taken 45 along line 9—9 of Fig. 7;

Fig. 10 is a view of the blank from which the container is constructed; and

Fig. 11 is a fragmentary sectional view taken 50 along line 11—11 of Fig. 7.

In the packaging of ice cream and other commodities a container which has met with favor consists of a collapsible fibrous body portion having the bottom member engageable therewith. Containers of this type have replaced metallic 55 containers to a considerable extent in the ice

cream industry. As will be recognized, important factors in the success of this type of container are the ease with which the bottom may be secured to the body portion of the container and the effectiveness of the resulting interlocking. 5

The container of the present invention may be erected or set up from collapsed condition by hand and in such condition is sufficiently sturdy to withstand hard use. The improved container 10 is constructed by providing a fibrous body portion of the usual type with interlocking openings adjacent its end portion and producing a suitable interlock between this body portion and a bottom member having a series of fingers along 15 its periphery. As shown in the drawings, one set of the fingers extends upwardly adjacent the inner wall of the body portion and the other set of the fingers is interlocked with the body portion. An inner bottom member is pressed 20 into engagement with the first mentioned set of tongue members and it is preferred to employ an inner body portion to add further strength to the assembled container.

The embodiment of the invention shown in 25 Fig. 1 consists of a body portion 10 constructed of a blank cut, scored and folded as shown in Fig. 3 to provide a locking strip 11 on each end of the blank, vertical score lines 12, and a series of bottom interlocking slots 13 adjacent the lower 30 end of the container. The body portion is produced by suitably securing together the opposite attaching flaps 11 so that the body portion assumes a tubular form which may be collapsed 35 by being flattened along diametrically opposite score lines 12. The bottom member is formed of a disk 14, such as is shown in Fig. 2. The disk is provided with a first series of tongues 15 which are adapted to lie adjacent the inner wall of the body portion and a second set of tongues 40 16 which may be interlocked with the openings 13 of the body portion. The diameter of the disk 14 is substantially the same as the inside diameter 45 of the body portion. Tongues 15 are scored at their point of jointure to the disk 14, and the tongues 16 may be scored additionally at a slightly extended distance from the center of the disk.

It will be noted that the tongues 16 in the embodiment shown in Figs. 1, 2 and 4 are of less 50 length than the tongues 15. This difference in length may be used to advantage in erecting the container. That is, the body portion may be distended into tubular formation and the disk 14 may be pressed downwardly therein from the top 55

of the body portion. This downward pressure causes both sets of tongues to fold upwardly. The disk 14 may be progressively pressed downwardly in the body portion of the container until 5 the shorter tongues 16 escape from the lower edge of the body portion. As the tongues 15 are longer than the tongues 16, the former will still be retained within the body portion. The resilience of tongues 16 will cause them to move outwardly 10 from within the body portion and the disk then may be pressed upwardly in the body portion until the bases of tongues 16 engage the lower edge of the body portion. Tongues 16 then may be interlocked in openings 13 in the customary 15 manner with interlocking elements of this type. That is, adjacent tongues 16 may be pressed together in overlapping relation and then inserted in the openings 13. Upon spreading the tongues apart an interlock is effected.

20 An inner body member 17, which may be formed of a blank similar to that shown in Fig. 3, but having a series of tongues 18, as shown in Fig. 8, along its lower edge, then may be inserted within the body portion and the fingers 25 or tongues 18 may be rotated inwardly into the position shown in Figs. 5, 6 and 8. That is, the inner body member is inserted within the outer body member with the tongues 18 resting adjacent the disk 14. An inner bottom member 19 30 then may be inserted within the inner body portion and pressed downwardly against the tongues 18. Preferably, this inner bottom member is slightly oversized so as to frictionally engage the tongues 15 between the inner and outer 35 body portions. This frictional engagement is increased when the container is filled with a commodity such as frozen ice cream.

In the modified form of the invention shown in Fig. 6 the tongue members 16 also lie along the 40 inner surface of the body portion and extend outwardly through the openings 13. In this embodiment the lower portions of tongues 16 are protected by the lower edge of the body portion.

In the embodiment of the invention shown in Figs. 7 to 11, the tongue members 15 are of substantially the same length as the tongue members 16, and one pair of the tongue members 16 45 is replaced by an integral connection of the disk 14 to the body member 10 along a score line 20. The disk 14 may be rotated about score line 20 50 into superimposed relation with respect to the body portion 10, and the securing flaps 11 then may be stapled together. The container may be erected merely by rotating the disk 14 downwardly into substantially horizontal position. In such cases, the fingers 16 are interlocked with the 55 openings 13 on the body portion from the inner side of the latter, as shown in Fig. 6. If the disk 14 is not secured within the body portion as 60 described, the blank may be formed into tubular

shape by securing flaps 11 together and the container may be erected by rotating fingers 15 inwardly to such an extent that they will protrude upwardly into the body portion when the disk 14 is rotated into horizontal position. The fingers 16 are interlocked with openings 13 from the outer side of the body portion, as shown in Figs. 8 and 9. An inner bottom member 17 having tongues 18 along its lower edge may be inserted within the outer body portion as shown in Fig. 8 and an oversized disk or inner bottom member 19 may be inserted to interlock the elements together. Where the outer bottom member 14 is integrally attached to the body portion 10, as shown in Fig. 10, the fingers 15 adjacent the 15 point of attachment are shortened.

A particular advantage of the structure described herein resides in the bracing effect produced by suspending the bottom member directly to the vertical walls of the body portion. The interlocking effect of this arrangement is increased by filling the container with a commodity, and, at the same time, there is produced the frictional engagement of the fingers 15 with the body portion. These two types of interlock combine to produce a sturdy and economical container.

Various changes and modifications of the structure described herein are possible without departing from the scope of the invention and such changes are intended to be included in the appended claims.

I claim:

1. A container of the type described, comprising a tubular body portion having openings adjacent one of its ends, a closure member of substantially the same diameter as said body portion, fingers on said closure member fitting adjacent the inside of said body portion, fingers on said closure member interlocked with said body portion through said openings, an inner body member having fingers extending adjacent said closure member, and an inner disk pressed into engagement with said inner body member to hold said first named fingers in frictional engagement with said body portion.

2. A container of the type described, comprising a tubular body portion having openings adjacent one of its ends, a closure member of substantially the same diameter as said body portion, a series of relatively long fingers and a series of relatively short fingers on said closure member, one of said series of fingers lying adjacent the inside of said body portion and the other of said series of fingers fitting adjacent the exterior of said body portion in interlocking relation with said openings, and an inner disk pressing said fingers into engagement with the body portion of said container.

HENRY K. POWELL. 60
